UNITED STATES PATENT OFFICE.

CLARENCE E. SMITH, OF WORCESTER, MASSACHUSETTS.

CARRIER OR COVER FOR CANTEENS OR WATER-BOTTLES, &c.

1,311,923.

Specification of Letters Patent.

Patented Aug. 5, 1919.

Application filed June 24, 1916. Serial No. 105,536.

To all whom it may concern:

Be it known that I, CLARENCE E. SMITH, a citizen of the United States, residing at Worcester, in the county of Worcester, 5 State of Massachusetts, have invented a certain new and useful Improvement in Carriers or Covers for Canteens or Water-Bottles, &c., of which the following is a specification, reference being had therein to the 10 accompanying drawings.

The invention has relation to carriers, covers, or jackets on the order of those in which canteens and water-bottles usually are carried. More especially, it relates to 15 the provisions for closing a cover about the shoulders and neck of a canteen, water-bottle, or the like, or the top of some other contained article, and fastening the cover in closed condition.

20 The nature of the improvement comprising the invention may be more clearly indicated by referring first to the regulation canteen carrier or cover now in use by the armed forces of the United States. The 25 said regulation canteen-carrier or cover has the upper portion of its back part formed or otherwise provided with two upwardly projecting, oppositely located, closure-ears or flaps. These are adapted to be bent or 30 folded forward over the shoulders of the canteen so that their free ends shall lie against the outer surface of the carrier or cover-front at somewhat widely separated places. Each closure-ear or flap has fastening means of its own, of the well-known 35 glove-fastener or stud-and-socket type, the stud-members of the two fastener-arrangements being fixed at laterally opposite points on the carrier or cover-front, and a 40 socket-member being fixed on each of the respective ears or flaps. With this construction and arrangement, employing separate fastening means for each closure-ear or flap, and fastening the respective closure-ears or 45 flaps to the carrier or cover-front at laterally opposite places, not only are duplicate fastenings employed, but each ear or flap is fastened or unfastened by operations and motions separate from and additional to 50 those by which the other ear or flap is fastened or unfastened. Thus, two separate fastening operations are required, and also two separate unfastening operations.

The objects of the invention are to sim-

plify the closing and fastening construction and arrangement of a carrier, cover, or jacket of the order aforesaid. Also, to reduce the number of fastener-devices employed and thereby effect a saving in cost, as well as reduce the expense of applying 60 fastenings in the process of manufacturing the carrier, cover, or jacket. Also, to make it easier for a soldier or other person to unfasten the closure-ears or flaps and open the latter, as for the purpose of enabling 65 him to withdraw the canteen, water-bottle, or other contained article from the carrier or cover when required, and to re-position the closure-ears or flaps and refasten them in closed position after replacing the canteen, water-bottle or other article within 70 the carrier or cover. Also, to improve the appearance of the carrier or cover.

The invention consists essentially in a carrier or cover having opposite closure-flaps which are so formed upon or applied to the carrier or cover-back, and also so shaped and proportioned in length, as to enable them to be brought together at their free ends upon the carrier or cover-front, 75 and also having a single fastener-device, or set of coacting fastener-devices, for the two flaps whereby they jointly may be secured in closed condition. Thereby, instead of the flaps being fastened separately in positions comparatively distant or remote from each other, they are brought together at their front ends and secured or fastened by one and the same fastener or set of fastener-devices. 80

90 The fastener-device or set of fastener-devices employed in carrying the invention into effect may vary in character, in practice. I have presented herein an illustrative embodiment of the invention in which 95 a stud is fixed in the front of the carrier or cover, at a middle point, and one of the flaps is furnished with an eye to fit over said stud, while the other flap is furnished with a socket-member to fit upon the portion of the stud which projects through the said eye.

In the drawings,—

Figure 1 is a front elevation of a canteen or water-bottle inclosed in a carrier or cover 105 made with the said illustrative embodiment of the invention, the said carrier or cover being closed and fastened.

Fig. 2 is an elevation with the carrier or cover unfastened, the canteen or water-bottle removed, and the flaps turned upward, and a portion of the carrier or cover-front 5 broken away.

Having reference to the drawings,—

The carrier-cover 1 will be shaped and proportioned in practice to inclose and fit a canteen, water-bottle, or other desired 10 article. The canteen or water-bottle which is incased within the said cover in Fig. 1 is or may be of well-known form, etc. At 2 is the projecting neck thereof. The carrier or cover 1 may be of any approved character 15 and construction except as indicated hereinafter in explaining the invention. At 3, 3^a, are closure-flaps such as have been mentioned, they being extensions from the back part of the carrier or cover.

In conformity with the invention, the closure-flaps 3, 3^a, are so formed upon or applied to the carrier or cover-back, and are so shaped and proportioned in length, as to enable them to be bent or folded over 20 the shoulders of the contained canteen, water-bottle, or other article so as to encircle the upstanding neck thereof, and brought together at their free ends upon the front of the carrier-cover. In this illustrative embodiment the said flaps are of such 25 length, etc., that the said free ends are adapted to overlap each other, as represented in Fig. 1, with one thereof lying upon the other. The form of fastener-device 30 shown in this instance is suited to this overlapping of the flaps. It comprises a headed fastener-stud 4 affixed to the middle of the front of the carrier or cover and projecting therefrom, an eye in one flap, as flap 3, pro- 35 tected by means of an eyelet or gromet 5 having an opening therethrough sufficiently large to pass easily and freely over the fastener-stud 4, and a socket-member 6 applied to the other flap, as flap 3^a. In closing 40 and fastening the carrier or cover, the flap 3 first is positioned with the eyelet or gromet 5 over and surrounding the fastener-stud 4, and then the flap 3^a is brought over the first flap, and the fastener-socket or 45 socket-member 6 is snapped in place upon the head of the fastener-stud. The operations 50 are simplified and made more convenient. A single operation will effect the unfastening.

The attainment of the stated objects of the invention will be obvious from the drawings and the foregoing description.

The invention is designed more particularly to be adapted in the case of carriers or 60 covers and the like made of woven material. A lining 7 of suitable material, usually felt,

will be provided in most cases, although this lining will sometimes be omitted.

In practice, the carrier or cover will have usually a hanger, of wire or other suitable 65 material, applied to the carrier or cover-back for engagement with a belt, shoulder-strap, or other means of support and carriage; or other means of attachment may be provided.

I claim as my invention:—

1. A carrier or cover for a canteen, water bottle, or the like, having opposite ears or flaps extending from one side of the same and adapted to be bent or folded over the 75 shoulders of the contained canteen, water-bottle, or other article so as to encircle the upstanding neck thereof, and overlapped at their free ends against the opposite side of the carrier or cover, and provided with 80 fastener-means for said overlapping ends to hold the carrier or cover in closed condition and having in its closed and fastened condition an opening that is occupied by the said upstanding neck.

2. A carrier or cover for a canteen, water-bottle, or the like, having the back thereof furnished with opposite ears or flaps adapted to be bent or folded over the shoulders of the contained canteen, water-bottle, or other article so as to encircle the upstanding neck thereof, and to overlap at their free ends, one of the said free ends having an eye, the other provided with one of the members of a stud-and-socket fastener, and the carrier or cover-front being provided with the other member of such fastener, the stud-member of said fastener passing through the eye in fastening the carrier or cover in closed condition.

3. A carrier or cover for a canteen, water-bottle, or the like having opposite ears or flaps extending from one side of the same and adapted to be bent or folded over the shoulders of the contained canteen, water-bottle, or other article so as to encircle the upstanding neck thereof, and to be brought together at their free ends against the opposite side of the carrier or cover, and fastener-means engaging with said ends jointly 105 to hold the carrier or cover in closed condition, said carrier or cover having in its closed and fastened condition an opening 110 that is occupied by the said upstanding neck.

In testimony, whereof I affix my signature in presence of two witnesses:

CLARENCE E. SMITH.
